UNITED STATES PATENT OFFICE.

CHARLES P. HOWE, OF COX CITY, OKLAHOMA.

OIL-WELL MECHANISM.

Application filed December 13, 1927. Serial No. 239,784.

The present invention relates to oil well mechanisms and particularly to mechanisms or devices for sealing-off oil wells at predetermined points for the purpose of raising the oil.

Many types of oil well packers and pumps have heretofore been designed or suggested but comparatively few types have been used in practice, and of those few types very few indeed have proven to be satisfactory in use. The object of the present invention is to provide an oil well mechanism having novel and improved features which may be incorporated with both packers and pumps, rendering both of these instrumentalities simpler and more rugged of construction and more efficient. The novel mechanism herein described is particularly applicable to pumps and by means of my invention it is possible to lower a complete pumping unit into a well casing by means of a cable, to automatically seal-off the casing at the desired elevation exteriorly of the pumping unit, to lift the oil by an ordinary pumping operation in which the pump piston is cable operated, to automatically break the seal when the pumping operation is terminated and to lift the pumping unit from the well by means of the cable, all of these operations being performed without the assistance of auxiliary piping or raising or lowering tools except in the event of breakage of the cable itself whereupon the unit may be readily lifted by means of an ordinary fishing tool.

Various forms or embodiments of the present invention may be devised without departing from the spirit thereof and in the accompanying drawings it is illustrated as incorporated in a packer and in a pump, the particular embodiments however being set forth by way of example only.

In the drawings:

Figure 1 is a vertical longitudinal section through a short length of oil well casing showing a packer embodying the invention positioned therein;

Figure 2 is a vertical section through a short section of oil well casing showing a pump constructed in accordance with the present invention positioned therein and arranged for pumping operations;

Figure 3 is a similar view but showing the parts in different positions, the unit being ready to be raised from the well by means of a cable; and

Figure 4 is a section on line 4—4 of Figure 1.

Referring first to Figures 1 and 4. Here the well casing is indicated at 10 and it will be understood that this casing is of the usual character and diameter. A relatively heavy metallic core is indicated at 11, this core having an upper conical portion 12 and a lower cylindrical portion 13, the outer surfaces of these portions being coaxial and the conical surface of the upper portion tapering downwardly toward the cylindrical outer surface of the lower portion. The core has an axial cylindrical aperture or bore 14 which extends entirely therethrough.

Upon the cylindrical outer surface of the lower portion 13 of the core is mounted a cylindrical slide 15, the downward movement of which is limited by the stop-ring 16. This slide has a plurality of longitudinal ducts 17 formed as grooves in its inner wall and through which grooves oil may freely pass under certain circumstances. It is threaded near its upper end to receive a threaded ring or collar 18, the outer diameter of which is only slightly less than the inner diameter of the well casing, and is also provided at its upper end with an outwardly extending annular flange 19. This flange extends within a groove formed in the inner wall of an expandable sleeve 20 preferably formed of rubber, the lower edge of the sleeve resting upon ring 18 and the sleeve being locked in such position by the inter-engagement of flange 19 and the walls of the groove within which it lies. To the bottom of slide 15 is secured as by a threaded connection, a coupling member 21 which has a sufficiently large inner diameter to clear the ring 16 but the lower end of which is reduced to threadedly engage the upper edge of a pipe 22, the inner diameter of which is substantially the same as the inner diameter of the longitudinal bore 14 of the core 11. A similar pipe 23 is connected to the upper end of the core by means of a threaded coupling 24.

When being freely lowered into the well the lower edge of sleeve 15 rests upon the stop-ring 16. When however the lower end of pipe 22 strikes the bottom of the well, or any obstruction therein, this pipe and slide 15 become stationary, while pipe 23 and the core continue their downward descent. As a result of this relative movement the conical member 12 of the core enters the expansi-

ble sleeve 20 and, engaging the upper edge of the same, expands outwardly to engage the inner wall of the casing. An efficient seal is therefore effected by the coaction of the 5 conical portion of the core and the expansible sleeve so that there is no communication between the space in the well casing below the cone 12 and that above the cone except through the central bore 14. As 10 a result of such sealing any gases which may be passing upwardly in the well are constrained to pass through the conduit 14 and the small pipes 22 and 23 and other pipes forming continuations of these pipes, so 15 that the lifting effect of the gas on the oil is accentuated and the well will continue to flow although the gas pressure is quite low. When it is desired to remove the device from the well it is only necessary to draw up 20 wardly the pipe 23 to which the core 11 is attached. The conical portion 12 of the core immediately passes without the expansible sleeve 20 and the seal is thereby broken. The entire unit may be then read- 25 ily drawn upwardly, the oil standing in the well above the seal leaking past the unit either around the outside of the expansible sleeve 20 or downwardly through the groove 17, so that the standing oil offers no sub- 30 stantial obstacle.

The pump of Figures 2 and 3 comprises a core 30 also having an upper conical member 31 and a lower cylindrical member 32, the conical outer surface of the upper member 35 tapering downwardly toward the cylindrical surface of the lower member and these surfaces being coaxially arranged. The core is provided with a longitudinal bore 33 which extends from its lower end 40 substantially to the top of the conical portion, but there terminates, a plurality of inclined passages 33' connecting the upper end of the bore with the space above the conical portion 31 and an axial cylindrical bore 34, of smaller diameter however than the main bore 33, extending through the upper portion of the core, this last mentioned passage 45 being adapted for the reception of a pump rod. Movable mounted upon the portion 32 of the core is a cylindrical slide 35 formed similarly to that described in connection with Figure 1, this slide likewise having a ring 36 threaded thereto which supports an expansible sleeve 37 preferably of rubber, the lower end of this sleeve being interiorly 50 grooved, as in the case of the packer just described, to receive an annular flange 38 extending outwardly from the upper end of the slide, whereby it is locked in the position illustrated.

To the lower end of the cylindrical portion 32 of the core, is secured by means of a suitable coupling member 40, a pump cylinder 41 having at its lower end a check 55 valve 42. Within the cylinder is positioned

a pump piston 43 of any well-known type which is adapted to be operated by a pump rod 44 extending axially upward through passage 34 of the core and to the upper end of which is connected a cable 45 by means 70 of which the pump rod and piston may be raised and lowered.

A perforated liner is indicated at 46 and it will be understood that this liner normally rests upon the bottom of the well and is of 75 smaller diameter than the well casing. The entire pumping unit may be lowered by means of cable 45 and, when suspended from the cable, the piston engages the upper end of the cylindrical bore 32 of the core, as 80 clearly shown in Figure 3. A unit may be freely lowered until the ring 36 engages the upper end of liner 46, as shown in Figure 3. The downward movement of the ring 85 is thereby halted and upon the continuance of the downward movement of the core 30 the conical portion 31 thereof enters the expansible ring 37 and causes the upper edge of the same to expand laterally to effectively seal that portion of the space within the 90 well casing lying below the conical member 31 from that portion above this member. The pump piston is then lowered somewhat further for pumping operations, this piston working from a point near the lower end of 95 the pump chamber, as shown in Figure 2, to a point near the upper end of the bore 32 of the core, but not contacting with the upper end wall of this bore in its ordinary operation. The oil entering through the small 100 aperture controlled by the check valve 42 is lifted upwardly and makes its way through the diagonal ducts 33 and into the well casing above the seal, thence to the top of the well.

Upon the discontinuance of the pumping operations the piston is lifted by means of the cable to the position in which it is shown in Figure 3, disengaging the conical portion 31 of the core from the expansible sleeve, 105 thereby breaking the seal. The entire unit may then be lifted to the top of the well for inspection, replacement, repair or removal to another well. In the event that the cable or pump rod breaks any ordinary type of 110 fishing tool may be lowered to engage the upper end of the core which is provided with annular serrations 50 to enable the fishing tool to conveniently take hold. When the pumping unit is being lifted through a 115 column of oil, the oil which stands above the same either leaks around the contracted expansible sleeve or passes down interiorly of the sleeve and through the longitudinal 120 grooves which are formed in the interior 125 wall of sleeve 35.

A very superior suction is obtained by the use of the pump above described. It is of simple and rugged construction, it is not easily choked by sand, it is inexpensive to 130

manufacture and has the particular advantage that it may be lowered, automatically sealed, operated, automatically unsealed and raised by one cable and entirely without the assistance of auxiliary instruments.

Having thus described the invention, what is claimed as new and desired to be secured by Letters Patent is:

1. In a device of the class described, in combination, a core having a fluid passage therethrough adapted to be lowered into an oil well casing and having a cylindrical surface and a downwardly tapering conical surface, the said surfaces being coaxial and the conical surface being above the cylindrical surface, a cylindrical slide mounted upon the cylindrical portion of the core and longitudinally movable thereon, a ring fixed on said slide exteriorly thereof, and an expandable sleeve mounted on said ring and extending upwardly toward the conical surface of the core, said conical surface being adapted to enter the sleeve and expand the same against the inner wall of a well casing upon the occurrence of relative movement of the slide and the conical surface in one direction, and to withdraw from said sleeve and permit the same to contract upon the occurrence of relative movement of the slide and conical surface in the opposite direction.
2. The combination set forth in claim 1 in which the slide has a plurality of substantially vertical ducts passing completely therethrough.
3. The combination set forth in claim 1 in which the slide has an annular flange at its top extending outwardly, and the expandable sleeve has a groove formed in its inner wall into which the said flange projects.
4. An oil well pump comprising a core

adapted to be lowered into a casing and having a cylindrical portion and a conical portion, the said portions being coaxial, the conical portion being uppermost and tapering downwardly toward the cylindrical portion, said core having a cylindrical bore extending through the cylindrical portion and continuing upwardly into and nearly through the conical portion, conduits leading from said bore to the upper surface of said conical portion, an axial aperture of reduced diameter extending through the top of said conical portion for the passage of a pump rod, a pump cylinder secured to the lower end of the cylindrical portion, a pump piston in said cylinder, a pump rod extending upwardly through said axial aperture whereby the piston may be operated for pumping or may be lifted to strike the upper end of said cylindrical bore to enable the entire assembly to be lifted by the pump rod, and means associated with the core and adapted to be operated by the conical surface thereof for automatically sealing off the well exteriorly of the core when the core is lowered to desired position and automatically breaking the seal when the core is lifted by means of the pump rod.

5. The combination set forth in claim 4 in which said last mentioned means includes a cylindrical slide movably mounted upon the cylindrical portion of the core and an expandable sleeve constrained to move with said slide, downward movement of the core relatively to the slide and sleeve bringing the conical surface of the core into contact with said sleeve.

In testimony whereof I hereunto affix my signature.

CHARLES P. HOWE.
